UNITED STATES PATENT OFFICE.

DANIEL JUSTIN SHAFFER, OF AURORA, ILLINOIS, ASSIGNOR OF ONE-HALF TO LEW E. WORTH, OF AURORA, ILLINOIS.

WATER HEATER.

Application filed February 16, 1924. Serial No. 693,315.

My invention relates to improvements in devices for heating water, more particularly to boilers or hot water heaters, and it consists in the combinations, constructions and arrangements herein described and claimed.

An object of my invention is to provide a device for heating water, of the type in which the water is caused to circulate through an inner tube and backwardly 10 through an outer tube, the latter being disposed in a combustion chamber, and in which novel and economical means is provided for holding the inner tube within the outer tube.

15 A further object is to provide a device in which a maximum flow of water is attained with a relatively simple structure, thereby reducing the manufacturing cost to a minimum.

20 Other objects and advantages will appear in the following specification, and the novel features of the invention will be particularly pointed out in the appended claims.

25 My invention is illustrated in the accompanying drawings—forming part of this application, in which—

30 Figure 1 is a sectional view of a heater constructed according to my invention, the water heating tubes being shown in section.

35 Figure 2 is a section along the line 2—2 of Figure 1, looking upwardly in the direction of the arrows,

Figure 3 is a section along the line 3—3 35 of Figure 4,

Figure 4 is a section along the line 4—4 of Figure 3, and

Figure 5 is a longitudinal section through a modified form of the device.

40 In carrying out my invention, I make use of any suitable casing 1. At 2 I have shown a grate, and below this an ash pit 3, access to the ash pit being by the door 4. Above the grate is a combustion chamber 5, having a fuel feed door 6. The parts described thus far are ordinarily found in any water heating device.

45 Disposed in the combustion chamber 5 is a series of vertically extending tubes or pipes. It will be observed from Figure 2 that certain of these pipes or tubes, such as those shown at 7, extend downwardly from headers 8 nearly to the grate 2. Other tubes 9 terminate some distance above the grate. This forms a space in which the

fuel may be placed for combustion. At the rear of the combustion space is a series of vertically extending water pipes 10 which are fed by a common supply pipe 11, and which communicate at their upper ends with 60 the headers 8. At 12 I have shown an exit flue for carrying away the products of combustion. It will be understood that the construction described is merely one example of the arrangements of the water tubes in a 65 combustion chamber, and that other arrangements might be made, without departing from the spirit of the invention.

The main feature of the invention lies in the tubes themselves and their connection with their respective headers. This is best shown in Figure 4. In this figure, it will be observed that the header 8 is provided with a series of bosses 13, into which are screwed pipes, such as those shown at 7 and 9, these pipes being closed at their lower ends by caps 14. At the upper ends of the pipes 7 and 9 is a segmental partition 15, whose purpose will be explained later.

50 Centrally disposed in each pipe 7 and 9 is an inner pipe or tube 16 which is spaced from the pipe 7 or 9 and which extends to the bottom. The pipes 16 are preferably slit and are flared outwardly so as to provide openings 17, which afford communication with the interior of the pipes 7 and 9. The pipes 16 are prolonged upwardly into the header 8, and on one side they have a cut-away portion 18 which is above the partition 15 and which faces in the direction 75 of the partition. On the opposite side of the pipe is a rod or bar 19 for holding the tube 16 in position.

55 From the foregoing description of the various parts of the device, the operation 95 thereof may be readily understood. The fire is built and the fuel is placed in the combustion chamber through the door 6 in the ordinary manner. Since the pipe 7 surrounds the fuel, the latter is in intimate 100 contact with the pipes and heats them to a high degree. Water is admitted through the supply pipe 11, and passes upwardly through the pipes 10 into the various headers 8, filling the pipes 7 and 9 and also the pipes 16. Owing to the highly heated condition 105 of the pipes 7 and 9, the water on the exterior of the pipes 16, but on the interior of the pipes 7 and 9, will be highly heated, and bubbles of steam will begin to form. 110

This renders the water on the exterior of the pipes 16 lighter than that within it, and consequently there will be a downward flow through the pipes 16, through the openings 17, and upwardly through the pipes 7 and 9 into the header. The purpose of the partitions 15 is to prevent interference with the flow of the colder water into the pipes 16, while the extension of the pipes 16 into 10 the header tends to divert the flow downwardly into the pipes 16. The greater part of the water, therefore, is compelled to pass downwardly into the highly heated pipes 7 and 9 in successive stages, thus getting the 15 benefit of close proximity to the hottest part of the combustion chamber, and making use of the maximum number of heat units which the fuel contains. The steam, in case the device is used to produce steam, passes on 20 upwardly through the pipes 20 into the header 21, from whence it may be used as needed.

It will thus be seen that I have provided a device, by means of which water may be 25 caused to circulate downwardly into the hottest part of the combustion chamber, and to return again to the same header.

The advantage just stated is best illustrated in the modification shown in Figure 5. 30 In this instance, I have applied my invention to an ordinary flue boiler, that is to say, a boiler in which the products of combustion pass through the boiler in flues, as distinguished from a water tube boiler, where the 35 products of combustion pass around tubes containing water. In Figure 5, the combustion chamber is shown at 22, and the products of combustion pass over the fire wall 23 to the rear of the boiler 24, and thence 40 forwardly through flues 25 to the stack 26. This is the ordinary construction. By placing the tubes 7 and 9 in the combustion chamber having interior tubes 16, as shown in Figure 4, there will be a circulation of

water from the boiler 25 downwardly 4 through the tubes in precisely the same manner as already explained. The tubes 7 and 9, however, are at the hottest part of the combustion chamber immediately surrounding the fuel, so that the radiating surface 5 is greatly increased, and the efficiency of the boiler is greatly increased as a result.

I claim:

1. The combination with a combustion chamber, of a header, means for introducing water at one end of said header, means for conveying water or steam away from the opposite end of said header, a plurality of pipes carried by and depending from said header, said pipes being arranged in alignment from one end of the header to the other, the upper ends of said pipes being in communication with the header, an interior pipe disposed in each of said first named pipes, the upper ends of the interior pipes 65 being extended into the header and having cut-away portions facing the inlet to the header, the bottoms of said interior pipes having free communication with the interior of said first named pipes, and a current- 70 checking partition between said interior pipes and said first-named pipes on the side of said interior pipes adjacent to said cut-away portions.

2. In a water heater, a header, a plurality of pipes carried by and depending from said header, each of said pipes having a segmental partition at the uppermost end, an interior pipe disposed in each of said first named pipes and provided with a shoulder 75 arranged to bear against said partition, said interior pipes being spaced from the first named pipes and communicating therewith near the bottoms, and a cap at the bottom of each of said first named pipes arranged to 80 engage the end of its interior pipe to hold said pipe between the cap and the shoulder.

DANIEL JUSTIN SHAFFER.
